UNITED STATES PATENT OFFICE.

JOHN I. NUNN, OF CLEVELAND, OHIO.

CHIN AND LIP ADJUSTER FOR CORPSES.

SPECIFICATION forming part of Letters Patent No. 402,764, dated May 7, 1889.

Application filed March 6, 1889. Serial No. 302,083. (No model.)

To all whom it may concern:

Be it known that I, JOHN I. NUNN, of Cleveland, in the county of Cuyahoga and State of Ohio, have invented certain new and useful 5 Improvements in Chin and Lip Adjusters; and I do hereby declare the following to be a full, clear, and exact description of the invention, such as will enable others skilled in the art to which it pertains to make and use the 10 same.

My invention relates to combined chin and lip adjusters, the same comprising a chin-support of ordinary construction, to which is added a lip-support adjustably connected, 15 preferably, with the chin-rest, to the end that in addition to supporting the under jaw of a deceased person the under lip may also be supported and made to assume a natural position.

20 In the accompanying drawings, Figure 1 is a front elevation. Fig. 2 is a side elevation, in section. Fig. 3 is a view of the lip-rest, showing it in position.

A represents the base having a hollow 25 standard, *a*, for receiving the stem *b* of the chin-rest *B*, member *a* having a set-screw, *a'*, for engaging stem *b* to hold the latter in adjustment.

The parts thus far described are of well- 30 known construction, and by resting the base on the breast-bone and adjusting the chin-rest

the under jaw is supported in position, closing the mouth.

It is also desirable to support the under lip in a natural position, and to this end I provide a 35 lip-rest, *C*. The latter may be constructed of any suitable material; but I find that vulcanized rubber is well adapted to the purpose, in that with gentle pressure applied the rubber adheres to the lip with sufficient force to hold 40 the lip in position without indenting or marking the lip. The lip-rest is more conveniently supported from the chin-rest, and for this purpose the chin-rest near the ends thereof is pierced for receiving the bows *c*, to which latter the lip-rest is attached, with thumb-screws 45 *b'* for engaging the bows to hold the chin-rest in place, bows *c* being preferably of spring metal, and by reason of the curvature of the bows the latter do not come in contact with 50 the chin.

What I claim is—

The combination, with a chin-adjuster, of a lip-adjuster, the latter being adjustably connected with and supported by the former, 55 substantially as set forth.

In testimony whereof I sign this specification in the presence of two witnesses.

JOHN I. NUNN.
